ATTORNEY

UNITED STATES PATENT OFFICE.

ANGELO DE TULLIO, OF ALBUQUERQUE, NEW MEXICO.

LAUNDRY-REGISTER.

1,266,426.

Specification of Letters Patent.

Patented May 14, 1918.

Application filed July 9, 1917. Serial No. 179,602.

To all whom it may concern:

Be it known that I, ANGELO DE TULLIO, a citizen of the United States, residing at Albuquerque, in the county of Bernalillo and State of New Mexico, have invented new and useful Improvements in Laundry-Registers, of which the following is a specification.

This invention is an improved laundry register for use in hotels, apartments, dwelling houses and the like for keeping a record of the articles placed in the laundry by any inmate or guest or from any room or suite of rooms, and also for keeping a record of dates in which the articles are sent to the laundry, when the articles are delivered, and when the articles are to be returned, and without the necessity of making entries with pencil or pen, on paper, or for writing a list of the articles.

The invention consists in a register having an individual designating column, articles designating and number designating columns, said individual designating column and said number designating columns having openings, and said openings of the number designating columns being arranged in line with the names of the articles in the articles column and the plugs for insertion in said openings, as hereinafter described and claimed.

In the accompanying drawings:—

Figure 1 is a plan of a laundry register constructed and arranged in accordance with my invention.

Fig. 2 is a detailed transverse sectional view of the same.

My improved laundry register comprises an oblong rectangular plate or board which in practice may be made of cardboard and is usually about three-sixteenths of an inch thick, and is of suitable length and width.

At the head the register is designated as such and is also provided with a space 1 for the name of a hotel, apartment house, or family, and also has an eyelet 2 to enable the register to be hung on a nail or the like support.

The register has a room or individual designating column 3 divided into consecutively numbered spaces 4 and each numbered space having an opening 5. An article designating column 6 is provided next to the column 3 and is divided into spaces 7 each of which has the name of some article

of wear or the like and such as are sent to the laundry. A dozens designating column 8 is next to column 6 and is provided with a series of sub-columns 9 which are consecutively numbered at the top as at 10 and each of which has spaces 11 opposite the spaces 7 and in line therewith and provided with openings 12.

A number designating column 13 for fractions of dozens, or numbers less than a dozen, is provided next to column 8 and is divided into sub-columns 14 which are consecutively numbered at the top as at 15 and which provide spaces 16 which align with the spaces 7 and 11, each space 16 having an opening 17.

A months date column 18 is provided next the column 13 and has consecutively numbered spaces 19 for the days of the month. A delivered date column 20 is next to the column 18 and has spaces 21 which align and correspond with the date spaces 19 and each of which has an opening 22. A return date column 23 is next to column 20 and has spaces 24 which align and correspond with the spaces 19 and 21 and each of which spaces 24 has an opening 25.

At the sides and partly across the bottom of the register are series of openings 27 which correspond in size and shape with the openings 5, 12, 17, 22 and 25 and for the reception of indicating plugs 28, which are preferably made of rubber and which can be removed from the openings 27 and inserted as may be required in the openings 5, 12, 17, 19, 22 or 25 to indicate each individual or person who sends articles to the laundry, the names and dozens or fraction of a dozen of each article so sent by him, and to also indicate the date when the articles are sent to the laundry and the date on which the same are to be returned. Hence my improved register enables a laundry list to be kept without writing the same and without the necessity of making entries with pencil or pen. The plugs may be changed as required, and as will be understood, from time to time to cause the register to preserve a correct account of all laundry transaction.

At the center of the bottom is a space 26 for a calendar and at opposite sides of said space 26 are spaces 27' which are inscribed with instructions as to the use of the register.

110

Having thus described my invention, I claim:

- The herein described laundry register comprising a plate or board having a room designating column, an articles designating columns, number designating columns, a month date column, and delivery and return date columns, said individual designating and said delivery and return date columns having openings, the said openings of the number designating columns being arranged in line with the names of the articles in the

articles column, and said delivery and return date columns also having openings, said month date column having day indicating 15 numbers opposite the openings of the delivery and return date columns, and plugs for insertion in any of said openings, the register being also provided with a series of openings for the reception of the plugs when 20 the latter are not in use.

In testimony whereof I affix my signature.

ANGELO DE TULLIO.
